DESIGN FOR A SCARF

Victor Unterreiner, Budapest, Hungary

Application April 20, 1939, Serial No. 84,407

Term of patent 3½ years

To all whom it may concern:

Be it known that I, Victor Unterreiner, a subject of Hungary, and a resident of the city of Budapest, in the country of Hungary, have invented a new, original, and ornamental Design for a Scarf, of which the following is a specification, reference being had to the accompanying drawing, constituting a part thereof.

The figure is a plan view of the scarf showing my new design.

I claim:

The ornamental design for a scarf, substantially as shown.

VICTOR UNTERREINER.
